Primary Examiner — Deanna L Pratt(74) *Attorney, Agent, or Firm* — McNair Law Firm, P.A.(57) **CLAIM**

The ornamental design for a multiple grip area pliers, as shown and described.

DESCRIPTION

FIG. 1 is a perspective view of a multiple grip area pliers in accordance with an embodiment of the present invention; FIG. 2 is a top view of the multiple grip area pliers of FIG. 1;

FIG. 3 is a bottom view of the multiple grip area pliers of FIG. 1;

FIG. 4 is a left side view of the multiple grip area pliers of FIG. 1;

FIG. 5 is a right side view of the multiple grip area pliers of FIG. 1;

FIG. 6 is a front view of the multiple grip area pliers of FIG. 1; and,

FIG. 7 is a back view of the multiple grip area pliers of FIG. 1.

The evenly-spaced broken lines illustrate portions of the multiple grip area pliers that form no part of the claimed design. The unevenly-spaced broken lines illustrate the bounds of the claimed design and form no part thereof.

1 Claim, 5 Drawing Sheets(56)
